UNITED STATES PATENT OFFICE.

FRANK MESKER AND THOMAS O. ARBEGUST, OF ST. LOUIS, MISSOURI,
ASSIGNORS TO MESKER & BROTHER, OF SAME PLACE.

WINDOW-FRAME.

SPECIFICATION forming part of Letters Patent No. 451,876, dated May 5, 1891.

Application filed May 8, 1890. Serial No. 350,530. (No model.)

To all whom it may concern:

Be it known that we, FRANK MESKER and THOMAS O. ARBEGUST, of St. Louis, Missouri, have jointly made a new and useful Improvement in Window-Frames, of which the following is a full, clear, and exact description.

The improvement relates to window-frames whose stiles are more or less composed of sheet metal, and it has special reference to mullioned windows; and it consists in the construction of the mullion, substantially as is hereinafter set forth and claimed, aided by the annexed drawings, making part of this specification, in which—

15 Figure 1 is a front elevation of a window-frame construction to which the present improvement is adapted. The frame is broken away at the right of the mullion; Fig. 2, a vertical section on the line 2 2 of Fig. 1; Fig. 20 3, a horizontal section on the line 3 3 of Fig. 1, and Fig. 4 a section upon an enlarged scale upon the line 3 3 of Fig. 1.

The same letters of reference denote the same parts.

25 Saving as the window-frame is modified or supplemented by the improvement under consideration it may be of any of the ordinary forms of construction which may be adapted for the embodiment therein of the 30 improvement. The frame A shown is a suitable one.

B B represent the lights divided by the mullion C, whose construction is the feature of the improvement. It is composed substantially of the two stiles c and c', the inside finish-board c² and the stud or filling-piece c³. The stiles are of sheet metal, shaped, as shown, to provide bearings c⁴ for the sashes D D and outside sash - stops c⁵ c⁵ and to 40 provide spaces or boxes c⁶ c⁶ to receive the weights E E, and the sheet is preferably in a single piece, extending from one edge c⁷ of the board c² outward and around and inward to the other edge c⁸ of the board c²,

and its face c⁹ is preferably paneled at c¹⁰ 45 partly to strengthen the mullion and partly to ornament it. The filling-piece extends from the board c² to the face c⁹, and it may be a single piece, as shown in Fig. 4, or in two or more pieces, as in Fig. 3. The piece c² 50 serves to strengthen the mullion, also to separate the boxes c⁶ c⁶. It is a desirable element in the construction, but not wholly essential.

F F represent the inside sash-stops, and G 55 G the parting-strips.

The board c² may be of metal. The frame A at its sides may have sheet-metal stiles, such as the stile H, and they may respectively adjoin sheet-metal columns, such as 60 the column I. The window-stool is shown at J. The window-frame at its top and bottom is constructed in the usual manner.

We claim—

1. A mullioned window-frame whose mullion is composed of the sheet-metal stiles, inside finish-board, and filling-piece, said stile being shaped to provide spaces to receive the sash-weights, substantially as described. 65

2. The combination, in a window-frame 70 mullion, of the double sheet-metal stile and the inside finish-board, said stile being shaped to provide spaces to receive the sash-weights, substantially as described.

3. The herein-described window-frame mullion, consisting of the double sheet-metal stile, the inside finish-board, and the filling-piece, 75 said mullion-face being paneled and said filling-piece extending from said board to said face, as described. 80

Witness our hands this 30th day of April, 1890.

FRANK MESKER.
THOMAS O. ARBEGUST.
